UNITED STATES PATENT OFFICE

CHARLES E. HENDRIX, OF JEFFERSON CITY, MISSOURI

WINDOW SHADE AND AWNING

Application filed April 21, 1930. Serial No. 445,880.

This invention relates to window shades and awnings. To illustrate the several features of the invention I have shown a shade device in which a web of material may occupy inclined positions to serve as an awning, and approximately vertical positions wherein it lies substantially parallel with a window. The term shade as herein used therefore refers to a substantially upright member conforming to the article known as a window shade, and it also extends to an inclined shade member serving as an awning.

One of the objects is to produce a simple and efficient means for retaining the shade material in the positions to which it may be adjusted as a window shade or awning.

Another object is to permit vertical adjustment of the device when it is positioned to form a vertical shade or an inclined awning. This is especially desirable when the device is used as an awning for an automobile, as the awning can then be adjusted for tall and short persons, or to merely serve as a visor at the top of the window.

A further object is to produce a device of this class that can be easily and quickly applied to windows of different widths. More specifically stated, this object includes a longitudinally adjustable roller on which the shade web is wound, an extensible device whereby the supports for the roller may be secured to windows of different widths, and a rod removably secured in the outer margin of the shade web. The several parts are preferably so arranged that the entire device can be easily secured to and removed from a window, without using a tool of any kind.

With the foregoing and other objects in view, the invention comprises the novel construction, combination and arrangement of parts hereinafter more specifically described and illustrated in the accompanying drawings, wherein is shown the preferred embodiment of the invention. However, it is to be understood that the invention comprehends changes, variations and modifications which come within the scope of the claims hereunto appended.

Fig. 1 is an inside view of the device applied to an automobile window.

Fig. 2 is a vertical section on the line 2—2 in Fig. 1, drawn to a larger scale.

Fig. 3 is a view similar to Fig. 2, showing how the locking dog at one end of the spring-actuated roller is located in an inoperative position when the device is in service.

Fig. 4 is a detail view showing a portion of the bracket at the opposite end of the roller.

Fig. 5 is a section on the line 5—5 in Fig. 1. 60

Fig. 6 is a fragmentary view, showing a portion of the shade web, and a portion of the rod removably secured in the outer margin of said web.

Fig. 7 is a view similar to Fig. 1, showing 65 the web positioned to serve as an awning.

Fig. 8 is a section on the line 8—8 in Fig. 7, drawn to a larger scale and illustrating two of the positions in which the awning may be located, a portion of a vertical guide being broken away to show the detents which secure the awning in the position illustrated by dotted lines.

Fig. 9 is a section on the line 9—9 in Fig. 8. 75

Fig. 10 is a fragmentary inside view, on a smaller scale, showing the awning in the position illustrated by dotted lines in Fig. 8.

Fig. 11 is a detail view of the tab or handle used in operating the device.

Fig. 12 is a view similar to Fig. 7, showing 80 a portion of the web as it appears when located in an approximately vertical position to serve as a window shade.

Fig. 13 is a section on the line 13—13 in Fig. 12, drawn to a larger scale. 85

Fig. 14 is a fragmentary view similar to the lower portion of Fig. 13, but showing the web in a higher position, and also showing detents to secure the web in this position.

Fig. 15 is a section on the line 15—15 in Fig. 13, drawn to a larger scale. 90

Fig. 16 is a perspective view of elements shown on the right hand side of Fig. 1 in spaced apart relation in the order of mounting.

The automobile window herein shown may have a frame of any kind including jambs 1 at the sides. Each of these jambs may be provided with a vertical groove 2 to receive the side edges of a vertically adjustable window 100.

pane 3. A bead 4 may be formed on each jamb, as shown in Fig. 5, which also illustrates the lining 5 in the vertical groove 2 and the facing 6 on the jamb 1.

- 5 7 designates the web of material adapted to occupy inclined and approximately vertical positions, as will be hereafter described. This web is wound around a roller 8 having the usual circular trunnion 9 at one end and 10 the usual flat extension 10 at the other end, said extension being secured to a rod 11 (Figs. 2 and 16) surrounded by the usual spring 12 which tends to rewind the web when it is unwound from the roller. One end of the 15 spring is secured to the rod and the other end is secured to the roller in the usual, or any suitable, manner which is not shown, as the invention is not limited to any means for securing the spring.
- 20 The ordinary spring-actuated shade roller includes a locking dog to prevent rewinding of the shade web when it is adjusted to the desired position, and in Fig. 3, I have shown a dog of this kind to retain the spring under 25 tension until the device is assembled, but the locking dog is thereafter ineffective, as other means are provided to prevent rewinding of the web, and I prefer to retain this web under tension when it is adjusted to its several positions.

30 The locking dog 13 (Fig. 8) is pivoted to the roller 8 and it is adapted to engage the stop shoulder on a disk 14 to prevent rewinding before the device is assembled, said disk being secured to the flat extension 10. However, when the device is assembled, the stop shoulder lies at the bottom of the then stationary disk 14, so the pivoted dog 13 will not cooperate with said shoulder.

40 To aid in locating the disk 14 and its stop shoulder (Fig. 3) in the position just referred to, I may so arrange a winding crank 15 on the flat extension 10 that the crank will indicate the position of said shoulder. For 45 example, if the crank 15 is arranged as shown in Figs. 2 and 3, it will extend downwardly when the stop shoulder on the disk 14 is at the bottom of the disk, and this will show how the roller should be mounted in its supports.

50 The crank is also used in tensioning the spring 12 before the device is applied to a window, and at this time the pivoted dog 13 (Fig. 3) cooperates with the shoulder on said disk 14 to retain the spring under tension.

55 The means for supporting the roller 8 includes brackets 16 extending from vertical bars 17 at the sides of the window, each bracket having an L-shaped slot 18 (Fig. 4). The rotary trunnion 9 lies in one of these slots, 60 while the flat extension 10 (Figs. 3 and 7) is located in the corresponding slot of the other bracket 16.

65 Each vertical bar 17 (Fig. 5) has a flange 19 extending into a groove 2, a bead 20 to receive the bead 4 on the jamb 1, and a fac-

ing 21 adapted to frictionally engage the jamb. This facing 21 is preferably a strip of friction material, such as plastic adhesive rubber compound which will conform to, and adhere to the jamb when the bar 17 is forced toward the jamb as hereafter described.

70 It will now be understood that when the device is assembled, the web 7 may be forcibly unwound from the roller 8, and the spring 12 always tends to rewind the web.

75 The outer margin of the web is folded and secured to form a hem 22, as shown in Fig. 7 and Fig. 8, which receives a rod 23, and the ends of this rod are removably located in short tubes 24 (Fig. 6) extending from arms 25, each arm having a slot 26 to receive a pivot 27 carried by a supporting member 28. The rod 23 and arms 25 form a substantially U-shaped yoke pivoted at 27 to the supporting members 28, but the simple rod 23 is merely telescoped with the short tubes 24, so the device can be easily assembled and taken apart.

80 Furthermore, in applying the device to a window, a side marginal portion of the web 7 can be severed, or torn off, to make the web conform to the width of the window, which is usual in devices of this kind, and the removable rod 23 can also be shortened by cutting off one of its ends to produce a pivoted yoke 85 of the desired width.

90 As shown by Figs. 2, 8, and 9, each supporting member 28 may be a sheet metal stamping, folded to embrace a vertical guide bar 29. The pivot 27 (Fig. 9) serves as a connection for the folded portions of the member 28. Each guide bar 29 is parallel with and slightly separated from one of the vertical bars 17, as shown in Figs. 9 and 10.

95 Each supporting member 28 is provided with a slot 30 to receive the extended inner end of one of the pivoted arms, and the bottom of this slot provides a stop, or abutment 31 to prevent upward movement of the pivoted arm, as shown in Fig. 8.

100 When the device is not in service, it is retained in the condition shown in Figs. 1 and 2 by means of the spring which tends to wind the web 7 onto the roller.

105 When the device is to be used as an awning, the tab or handle 32 is pulled to move the web to an inclined position suggested by Figs. 7, 8 and 10, and the arms 25 are then moved longitudinally to locate the extended inner ends of said arms in the slots 30. The 110 stops, or abutments 31, formed by the bottom walls of said slots, then prevent rewinding of the web while it is held under tension by the spring 12 in the roller 8.

115 The supporting members 28 are slidable on the vertical guide bars 29, so the awning can be adjusted to different positions, as suggested in Fig. 8, and when in any of these positions, the web is held under tension by the spring in the shade roller.

To illustrate a suitable means for securing the awning in the different positions, I have shown yieldable detents 33 formed by bending the metal of the bar 17 (Figs. 7, 8 and 10) and adapted to cooperate with the upper edges of the slideable supporting members 28 to prevent accidental displacement of said members 28.

The web 7 may also occupy approximately 10 vertical positions, as suggested in Figs. 12, 13 and 14, and the tension of the web 7 then tends to elevate the arms 25. In other words, the arms 25 may be moved from approximately upright positions wherein they extend 15 upwardly from the pivots 27, as shown in Fig. 1, to intermediate positions wherein they extend outwardly from the window to position the web as an awning (Fig. 8), and said arms are movable from the intermediate positions to depending positions wherein they extend downwardly from the pivots (Figs. 12, 13 and 14) to position the web as a window shade.

In all of its positions, the spring tends to 25 rewind the web, and to prevent this rewinding when the web is moved to its approximately vertical position, I have shown (Figs. 12, 13, 14 and 15) stop members 34 connecting the lower ends of the vertical guides 29 to the 30 vertical bars 17.

These stop members 34 are so arranged in the paths of arms 25 that they prevent continued inward movement after the end of the web is moved inwardly across the vertical 35 plane in which the axis of the pivots 27 is located, said arms and web being free to move outwardly, away from the stop members, in response to outward pressure overcoming the spring 12 which holds the web 7 under tension.

When the web 7 is located in its approximately vertical position, it can be adjusted vertically, as the stop members 34 do not interfere with the vertical adjustment of the 45 slideable members 28. When the web is in this approximately vertical position, the window pane 3 would usually serve as a stop to prevent undue outward displacement of the web, even though the motion of an automobile 50 equipped with the device tends to shift the arms 25 from the stops 34.

The supporting means to secure the device to a window includes the pair of bars 17 and the adhesive rubber facings 21 adapted to engage the jambs. If the bars 17 are properly forced away from each other, the entire device will be securely attached to a window.

To illustrate the foregoing feature of the invention, I have shown a means whereby the 60 vertical bars 17 are forced away from each other to secure the device to the jambs. This means is an extensible thrust device arranged between the vertical bars 17, and as an illustration of a suitable thrust device, I have 65 shown a horizontal rod 36 secured to one of

said vertical bars 17, a socket 37 extending from the other bar, a second rod 35 having one of its ends rotatably secured in said socket 37 and its other end alined with the rod 36, and a screw threaded member 38 connecting 70 said rods. A simple eye 39 (Fig. 1) may be secured to the member 38 to dispense with the use of inconvenient tools in securing the device to a window. This eye may also serve to connect the threaded member 38 to the 75 rod 35.

The shade web 7 and the rod 23 at its outer margin may be trimmed, as previously described, for windows of different widths, and the same is true of the rod 35. This will require a corresponding variation in the length of the roller 8.

I claim:

1. An awning comprising a roller, a web wound thereon, a pair of vertical bars adapted to be secured to the sides of a window frame, each of said vertical bars being provided with a supporting member, a pair of arms secured to the outer edge of said web and pivoted to said supporting members, said arms being movable on their pivots to locate the web in its extended position, said supporting members being provided with stops engaging portions of said arms to limit the upward pivotal movement of said arms when the web occupies its extended position, and a spring tending to rewind the web on the roller, so as to force said arms onto said stops.

2. An awning comprising a roller, a web wound thereon, a pair of vertical bars adapted to be secured to the sides of a window frame, supporting members secured to said bars, a yoke including a member in the outer edge of said web and arms extending from the ends of said member and provided with elongated slots, pivots securing said arms to said supporting members, said arms being movable on their pivots to locate the web in its extended position, stop members located near said pivots to prevent upward pivotal movement 100 of said arms when the web is extended, the inner ends of said arms being extended from the pivots to provide retaining members, said arms being loosely secured at the pivots and movable longitudinally to move their extended inner ends into and out of engagement with said stop members when said web occupies its extended position, and a spring tending to rewind said web on said roller, so as to retain the extended inner ends of said 105 arms in engagement with said stop members.

3. An awning comprising a roller, a web wound thereon, a pair of vertical bars adapted to be secured to the sides of a window frame, a yoke including a member extending across and secured to the outer edge of said web and arms extending from the ends of said member, supporting members, pivots securing said arms to said supporting members, said arms being movable on their pivots to 115 120 125 130

locate the web in its extended position, said supporting members being provided with openings adjacent to said pivots, each of said arms having a longitudinal slot to receive the pivot and the inner end of each arm being extended from the pivot to provide a supporting member, said arms being movable longitudinally to move their extended inner ends into and out of said openings when said web 10 occupies its extended position, the lower walls of said openings serving as stops to limit the upward pivotal movement of the arms, and a spring tending to rewind said web on said roller, so as to retain the inner ends of said 15 arms in said openings.

4. An awning comprising a roller, a web wound thereon, a pair of substantially vertical guides adapted to lie at opposite sides of a window frame, supporting members slidably 20 secured to said guides, a pair of arms having an elongated slot secured to the outer edge of said web and pivoted to the slidable supporting members, said arms being movable on their pivots to locate the web in its extended 25 position, and said slidable supporting members being adjustable along said guides while the web is extended, so as to locate the outer edge of the web in different horizontal planes.

5. An awning comprising a roller, a web wound thereon, a pair of vertical bars adapted to lie at opposite sides of a window frame, said vertical bars being provided with substantially vertical guides and supporting 35 members slidable thereon, a pair of arms secured to the outer edge of said web and pivoted to said slidable members, said arms being movable on their pivots to locate the web in its extended position, said slidable members being provided with means to limit the upward pivotal movement of said arms when the web occupies its extended position, and a spring tending to rewind the web on the 40 roller, so as to maintain the web under tension when said slidable members are adjusted to different positions on said guides.

6. An awning comprising a roller, a web wound thereon, a pair of vertical bars adapted to be secured to the sides of a window frame, each of said vertical bars being provided with a substantially vertical guide and a supporting member slidable along said guide, a pair of arms secured to the outer edge of said web and pivoted to the slidable 50 supporting members, said arms being movable on their pivots to locate the web in its extended position, said supporting members being provided with stops engaging portions of said arms to limit the upward pivotal 55 movement of said arms when the web occupies its extended position, and a spring tending to rewind the web on the roller, so as to force said arms onto said stops, said supporting members being movable along the guides 60 while the arms and web are extended.

7. An awning comprising a roller, a web wound thereon, a pair of substantially vertical guides adapted to lie at opposite sides of a window frame, supporting members slidably fitted to said guides, a yoke including a 70 member in the outer edge of said web and arms extending from the ends of said member, pivots securing said arms to said slidable supporting members, said arms being movable on their pivots to locate the web in its extended position, stop members carried by said supporting members to prevent upward pivotal movement of said arms when the web is extended, the inner ends of said arms being extended from the pivots to provide a 75 retaining member, said arms being loosely secured at the pivots and movable longitudinally to move their extended inner ends into and out of engagement with said stop members when said web occupies its extended 80 position, and a spring tending to rewind said web on said roller, so as to retain the inner ends of said arms in engagement with said stop members, said slidable supporting members being movable along said guides when the web is extended, so as to locate the outer edge of the web in different positions.

8. An awning comprising a roller, a web wound thereon, a pair of substantially vertical guides adapted to be secured to opposite sides of a window frame, supporting members slidably secured to said guides, a pair of arms secured to the outer edge of said web and pivoted to the slidable supporting members, said arms being movable on their pivots to locate the web in its extended position, said slidable supporting members being adjustable along said guides while the web is extended, so as to locate the outer edge of the web in different horizontal planes, and locking elements retaining said slidable supporting members in the positions to which they are adjusted, said locking elements comprising yieldable detents cooperating with said slidable supporting members.

9. An awning comprising a roller, a web wound thereon, a pair of substantially vertical guides adapted to be secured to opposite sides of a window frame, supporting members slidably secured to said guides, a pair of arms secured to the outer edge of said web and pivoted to the slidable supporting members, said arms being movable on their pivots to locate the web in its extended position, a spring tending to rewind the web on the roller, stops carried by said slidable supporting members and cooperating with said arms to retain the web in its extended condition, said slidable supporting members being adjustable along said guides while the web is extended, so as to locate the outer edge of the web in different horizontal planes, and detents retaining said slidable supporting members in the positions to which they are adjusted.

10. An awning comprising a roller, a web wound thereon, a pair of substantially vertical guides adapted to be secured to opposite sides of a window frame, supporting members 5 slidably secured to said guides, a pair of arms secured to the outer edge of said web and pivoted to slidable supporting members, said arms being loosely mounted on their pivots to locate the web in its extended position, a 10 spring tending to rewind the web on the roller, stops carried by said slidable supporting members and cooperating with said arms to retain the web in its extended condition, said slidable supporting members being adjustable along said guides while the web is extended, so as to locate the outer edge of the web in different horizontal planes, and detents retaining said slidable supporting members in the positions to which they are adjusted, said detents comprising yieldable bars associated with said guides and provided with extended detents in different planes adapted to engage said slidable supporting members.

11. In a combined window shade and awning, a roller, a web wound thereon, a pair of arms secured to the outer end of the web, a pair of supporting members adapted to be secured to the sides of a window frame, pivots connecting said arms to said supporting members, said arms being movable on the pivots from approximately upright positions wherein they extend upwardly from the pivots to intermediate positions wherein they extend outwardly from the window to position the web as an awning, and said arms being movable from said intermediate positions to depending positions wherein they extend downwardly from the pivots to position the web as a window shade, stop members 25 adapted to prevent return movement of said arms when they are located in said depending positions, and a spring tending to rewind said web on said roller, so as to retain said arms in engagement with said stop members.

12. In a combined window shade and awning, a roller, a web wound thereon, a pair of arms secured to the outer end of the web, a pair of supporting members adapted to be secured to the sides of a window frame, pivots connecting said arms to said supporting members, said arms being movable on the pivots from approximately upright positions wherein they extend upwardly from the pivots to intermediate positions wherein they extend outwardly from the window to position the web as an awning, and said arms being movable from said intermediate positions to depending positions wherein they extend downwardly from the pivots to position the web as a window shade, stop members adapted to prevent return movement of said arms when they are located in said depending positions, and a spring tending to rewind said web on said roller, so as to retain said arms in

engagement with said stop members, said stop members being so arranged that they cooperate with said pivoted arms to prevent continued inward movement after the end of the web is moved inwardly across the vertical plane in which the axis of the pivots is located. 70

13. In a combined window shade and awning, a roller, a web wound thereon, a pair of arms secured to the outer end of the web, a pair of supporting members adapted to be secured to the sides of a window frame, pivots connecting said arms to said supporting members, said arms being movable on the pivots from approximately upright positions wherein they extend upwardly from the pivots to intermediate positions wherein they extend outwardly from the window to position the web as an awning, and said arms being movable from said intermediate positions to depending positions wherein they extend downwardly from the pivots to position the web as a window shade, stop members adapted to prevent return movement of said arms when they are located in said depending positions, and a spring tending to rewind said web on said roller, so as to retain said arms in engagement with said stop members, said stop members being so arranged in the paths of said arms that they only prevent continued inward movement after the end of the web is moved inwardly across the vertical plane in which the axis of the pivots is located, said arms and web being free to move outwardly, away from said stop members, in response to an outward pressure overcoming said spring. 90

14. In a combined window shade and awning, a roller, a web wound thereon, a pair of arms secured to the outer end of the web, a pair of supporting members adapted to be secured to the sides of a window frame, pivots connecting said arms to said supporting members, said arms being movable on the pivots from substantially upright positions wherein they extend upwardly from the pivots to intermediate positions wherein they extend outwardly from the window to position the web as an awning, and said arms being movable from said intermediate positions to depending positions wherein they extend downwardly from the pivots to position the web as a window shade, means for preventing return movement of said arms when they are located in said intermediate and depending positions said pivots being adjustable vertically on said supporting members to locate the edge of the web in different horizontal planes when the arms occupy said depending positions, and a spring tending to rewind said web on said roller. 110

15. In a combined window shade and awning, a roller, a web wound thereon, a pair of arms secured to the outer end of the web, a pair of supporting members adapted to be

secured to the sides of a window frame, pivots connecting said arms to said supporting members, said arms being movable on the pivots from approximately upright positions wherein they extend upwardly from the pivots to intermediate positions wherein they extend outwardly from the window to position the web as an awning, and said arms being movable from said intermediate positions to depending positions wherein they extend downwardly from the pivots to position the web as a window shade, stop members adapted to prevent return movement of said arms when they are located in said depending positions, and a spring tending to rewind said web on said roller, so as to retain said arms in engagement with said stop members, and said pivots being adjustable vertically along said supports, to locate the end of the web in different positions while said stop members are cooperating with the pivoted arms.

16. In a device of the class described, a pair of vertical bars adapted to lie at the jambs of a window, a shade roller rotatably supported by said vertical bars, a web wound on said roller, and means whereby said vertical bars are forced away from each other to secure the device to the jambs.

17. In a device of the class described, a pair of vertical bars adapted to lie at the jambs of a window, a shade roller rotatably supported by said vertical bars, a web wound on said roller, and means whereby said vertical bars are forced away from each other to secure the device to the jambs, said means comprising an extensible thrust device arranged between said vertical bars.

18. In a device of the class described, a pair of vertical bars adapted to lie at the jambs of a window, a shade roller rotatably supported by said vertical bars, a web wound on said roller, and means whereby said vertical bars are forced away from each other to secure the device to the jambs, said means comprising alined rods between said vertical bars and screw threads connecting said rods.

19. In a device of the class described, a pair of vertical bars adapted to lie at the jambs of a window, a shade roller rotatably supported by said vertical bars, a web wound on said roller, and means whereby said vertical bars are forced away from each other to secure the device to the jambs, said means comprising a horizontal rod secured to one of said vertical bars, a socket extending from the other vertical bar, a second rod having one of its ends rotatably mounted in said socket and its other end alined with the first mentioned rod, and a screw threaded member connecting said rods.

20. In a device of the class described, a pair of vertical bars adapted to lie at the jambs of a window, each of said vertical bars being provided with a facing of friction material

adapted to engage the jambs, a shade roller supported by said vertical bars, a web wound around said roller, and means whereby said vertical bars are forced away from each other to frictionally secure said friction material between said vertical bars and jambs. 70

21. In a device of the class described, a pair of vertical bars adapted to lie at the jambs of a window, each of said vertical bars being provided with a facing of flexible friction material adapted to engage the jambs, a shade roller supported by said vertical bars, a web wound around said roller, and means whereby said vertical bars are forced away from each other to frictionally secure said friction material between said vertical bars and jambs. 75

22. In a device of the class described, a pair of vertical bars adapted to lie at the jambs of a window, each of said vertical bars being provided with a facing of rubber friction material adapted to engage the jambs, a shade roller supported by said vertical bars, a web wound around said roller, and means whereby said vertical bars are forced away from each other to frictionally secure said friction material between said vertical bars and jambs. 80

23. In a device of the class described, a pair of vertical bars adapted to lie at the jambs of a window, each of said vertical bars being provided with a facing of plaster, adhesive rubber friction material adapted to engage the jambs, a shade roller supported by said vertical bars, a web wound around said roller, and means whereby said vertical bars are forced away from each other to frictionally secure said friction material between said vertical bars and jambs. 95

In testimony that I claim the foregoing I 105 hereunto affix my signature.

CHARLES E. HENDRIX.
